UNITED STATES PATENT OFFICE.

FREDERICK H. MILLER, OF NEW YORK, N. Y.

TOY VEHICLE.

1,402,636.

Specification of Letters Patent.

Patented Jan. 3, 1922.

Application filed October 20, 1920. Serial No. 418,163.

To all whom it may concern:

Be it known that I, FREDERICK H. MILLER, a citizen of the United States, and a resident of the city of New York, Ridgewood, 5 borough of Queens, in the county of Queens and State of New York, have invented a new and Improved Toy Vehicle, of which the following is a full, clear, and exact description.

10 This invention relates to toy vehicles, and has particular reference to one which is built to imitate an automobile.

An object of the invention is to provide a toy vehicle fashioned to imitate an automobile, which is unique in form and structure 15 and has the appearance of high-speed automobiles.

Another object of the invention is to provide a body portion for a toy vehicle which 20 imitates the long narrow body portions of high-speed automobiles.

A further object resides in the provision 25 of a body portion of one piece of material, to simulate at the front end thereof the effect of an automobile radiator.

A still further object resides in the provision of means whereby the operating parts 30 of the vehicle are closed from contact with the operator as much as possible to prevent soiling the clothes of the child.

Another object resides in the provision 35 of the particular arrangement and construction of parts to be hereinafter described and claimed and shown in the accompanying drawings.

The invention is shown in the drawings, of which—

Figure 1 represents a perspective view of 40 the entire vehicle with a boy seated thereon to illustrate the manner in which the vehicle may be operated;

Figure 2 is a side elevation of the vehicle;

Figure 3 is an inverted plan view of the same;

45 Figure 4 is a front elevation;

Figure 5 is a detail section taken through the rear of the vehicle and showing the rear axle and sprocket connection;

Figure 6 is a detail view of the connection 50 between the rear shaft and one of the driving wheels;

Figure 7 is a side view of the connection shown in Fig. 6;

55 Figure 8 is a detail view of the connection between the rear shaft and another wheel; and

Figure 9 is a side view of the connection shown in Figure 8.

As shown in the drawings, the vehicle comprises a long, thin, high body portion 1, which is preferably made of wood. This body portion is cut away along its upper edge midway of its length to provide a recess portion 2 at the rear of which a seat 3 is suitably fastened. The front edge of this depressed portion 2 is curved upwardly as shown at 4, and then extends forwardly and downwardly in a line 5, imitating in effect the sloping hood of an automobile. The rear edge of the depressed portion 2 provides a backing for a seat back 6. The rear edge of the body portion from the seat back 6 slopes in a smooth curve 7 downwardly to the lower edge of the bottom portion. The front portion of the body 8 is integral with the main body portion but is seemingly separate therefrom, having a thin groove 9 around the top and side edges of the body portion. This groove 9 seemingly separates the portion 8 from the body portion 1, and by having the line 5 where it meets the portion 8 depressed slightly below the level of the top edge of said portion, the effect of a radiator is given. A spool 10 of any suitable material, such as wood, may be placed on top of this portion 8 to simulate a radiator cap. A shaft 11 extends through the body portion forward of the depressed portion 2 and at its upper end is provided with a steering wheel 12. The lower end of this shaft 11 is provided with an arm 13 which, at its opposite ends, is connected to links 14 which are in turn fastened in any suitable manner to a front axle housing 15.

Along a suitable portion of the lower edge of the body portion, and extending into the body portion to varying depths, there is provided a slot 16. The forward portion of this slot is cut out deeper into the body portion than the rear portion, as shown in Figure 2. In this slot a chain 17 is adapted to run and is mounted on a sprocket wheel 18 at the forward end thereof and a sprocket wheel 19 at the rear end thereof. The sprocket wheel 18 is mounted on a shaft 20 journaled in the walls of the body portion and connected to pedals 21. Attached to the lower edge of the body portion adjacent the sprocket 18 is a protecting casing or 105 housing 22 which may be fastened thereto in any suitable manner. This housing or

casing may be made of wood and is adapted to close in or embrace the lower portion of the sprocket 18 and the chain 17.

The sprocket 19 is mounted on a shaft 23. 5 This shaft is suitably journaled in a housing 24, which may be made of a single piece of wood and is suitably attached by screws, such as 25, to the lower rear edge of the body portion. This housing 24 is provided 10 with an apertured portion 26 in which the sprocket 19 moves together with the chain 17. It will, therefore, be observed that substantially the entire chain and both of the sprockets of this vehicle are enclosed from 15 view and from contact with the limbs or clothing of the operator.

The housing 15 forms a bearing for the shaft 27 at the front of the machine and is connected to the front lower edge of the 20 body portion by a bolt 28 which permits the housing portion to be rotated with respect to the body portion in any well-known manner.

As shown in Figure 6, one end of the shaft 25 23 is squared on its end portion, the remaining portion of the shaft being round. The hub 29 of one of the wheels surrounds the round portion of the shaft and is connected by bolts 30 to a plate 31 which embraces the squared end of the shaft and is provided with a square aperture. By this means one of the wheels of the rear shaft is adapted to be moved positively by the rotation of the shaft 23, whereas, as shown in 35 Figures 8 and 9, the other wheel or shaft 23 is not positively connected to the shaft but is merely rotatably mounted thereon in the usual manner.

It will, therefore, be apparent that I have 40 provided a simple, compact toy vehicle simulating the high-speed automobile, in which the operating parts, contact with which

might soil the garments of the operator, are closed in in a very simple and substantial manner. The simulation of a high-speed 45 automobile is given and achieved by reason of the formation of the body portion of a single piece of material and cutting the same to separate it from the main body portion to give the effect of a radiator. 50

What I claim is:

1. A vehicle body comprising a single piece of material having a lower face and a slot therein, a sprocket and chain co-operatively associated with the body portion and adapted to be disposed in said slot whereby the sprocket and chain are substantially enclosed by the slot, said slot being of a width only slightly larger than the width of the sprocket and chain, whereby the slot acts 60 as a substantially complete housing for the sprocket and chain.

2. A toy vehicle comprising a body portion made of a single piece of material having a slot in its lower face, wheels associated with said body portion, a sprocket and chain associated with said wheels and body portion to actuate the wheels, said sprocket and chain being located substantially within the slot, and cover portions disposed on the 70 lower face of the body portion to enclose the projecting ends of the sprocket and chain.

3. A toy vehicle comprising a body portion, a pair of wheels associated therewith, 75 a shaft connecting said wheels, a sprocket associated with said shaft, a housing for said shaft, said housing being attached to the body portion, and a channel portion in said housing adapted to enclose the sprocket, said 80 housing and channel portion being made of one piece of material.

FREDERICK H. MILLER.
